DESIGN FOR A TEXTILE FABRIC

Dorothy S. Smith, New York, N. Y.

Application January 28, 1938, Serial No. 74,625

Term of patent 3½ years

To all whom it may concern:

Be it known that I, Dorothy S. Smith, a citizen of the United States, residing at New York city, in the county and State of New York, have invented a new, original, and ornamental Design for a Textile Fabric, of which the following is a specification; reference being had to the accompanying drawing, forming part thereof.

The figure is a plan view of a textile fabric, showing my new design.

I claim:

The ornamental design for a textile fabric, substantially as shown.

DOROTHY S. SMITH.
